CLAIM

The ornamental design for a buckle as shown and described.

DESCRIPTION

FIG. 1 is a front perspective view of a buckle showing our new design.

FIG. 2 is a rear perspective view of the buckle of FIG. 1.

FIG. 3 is a front elevational view of the buckle of FIG. 1.

FIG. 4 is a rear elevational view of the buckle of FIG. 1.

FIG. 5 is bottom plan view of the buckle of FIG. 1, the top being a mirror image thereof.

FIG. 6 is a left side elevational view of the buckle of FIG. 1; and,

FIG. 7 is a right side elevational view of the buckle of FIG. 1.

The evenly spaced broken lines in the drawings represent portions of the buckle and form no part of the claimed design. The dot-dash broken lines represent a boundary and form no part of the claimed design.

1 Claim, 3 Drawing Sheets
